11 Claims. (Cl. 170—160.58)

This invention relates to improvements in propellers and, more particularly, to propellers in which the blades are detachably connected to the hub. Still further, but without restriction thereto, the improvements afforded by the invention are admirably adapted for use in propellers in which the blades are variably adjustable in pitch relative to the hub. Also, although the principles of the invention are well suited for use in propellers of marine-type, said principles likewise may be incorporated in impellers used in pumps, for example, particularly where the impellers have detachable blades or the blades are adjustable relative to the hub, or both.

At present, a number of different expedients are used for attaching blades to the hubs of either propellers or pump impellers of the type now used, including both blades which are adjustable as to pitch, and non-adjustable. There are certain advantages, particularly for manufacturing purposes, in making propellers and impellers with detachable blades. Further, should a single blade become damaged during use, it is only necessary to replace that blade and this frequently can be done without removing the propeller, for example, from the ship. Large marine propellers for example are costly and the advantage of being able to replace only a single damaged blade as distinguished from having to repair a fixed blade, of a propeller or replace the entire propeller, is obvious.

Some of the present means used for connecting detachable blade propellers to the hubs therefor include complementary threads on the blade shanks and sockets of the hub, and direct bolting of flanges formed, for example, on each blade to either a socket or the exterior surface of the propeller hub. The same is true relative to certain pump impellers. The principal disadvantage of this type of connecting means is that the blades loosen relative to the hub during service and, frequently, the means for tightening the blades relative to the hub are accessible from inside the hub only, which necessitates removing the propeller from the ship or pump to effect such tightening. Still further, such attaching means frequently are very cumbersome in size.

The present invention affords a construction adapted for incorporation in either a propeller or pump impeller which has none of the disadvantages referred to above relative to presently used constructions of this type. It is the principal object of the invention to provide means for rigidly and firmly connecting detachable blades to the hub of a propeller or pump impeller, the connecting means, in the preferred embodiment of the invention, being operable by mechanism accessible externally of the hub but which nevertheless affords no impedance to the operation of the propellers.

A further object of the invention is to provide mechanism having the foregoing characteristics but which is compact in size and hence requires a propeller hub of only minimum size, said construction being adaptable with equal facility to propellers or pump impellers having blades that are only detachable or which also may be

adjustable to permit the varying of the pitch thereof relative to the hub which supports them.

Still another object of the invention is to include mechanism by which not only may the blades be attached to and disconnected from the propeller hub by means operable entirely from the exterior of the hub but said mechanism also operates to insure positive disconnection of the connecting means from its operative position relative to the blades, thereby to free the blades for separation from the hub.

Details of the foregoing objects and of the invention, as well as other objects thereof, are set forth in the following specification and illustrated in the accompanying drawings comprising a part thereof.

15 In the drawings:

Fig. 1 is a perspective view of an exemplary propeller embodying the principles of the present invention.

Fig. 2 is a longitudinal sectional view of the propeller shown in Fig. 1 but illustrated on a larger scale, one of 20 the blade receiving socket members being shown in section in this figure, while another of said socket members is not sectioned.

Fig. 3 is a sectional view of the propeller shown in Fig. 2, taken on the line 3—3 of Fig. 2.

25 Fig. 4 is a transverse, fragmentary sectional view of the socket means for mounting the blades in the hub of the exemplary mechanism illustrated in the foregoing figures but shown on a larger scale than in any of said figures.

For purposes of facilitating the illustration of the principles of the present invention with a minimum of description and illustrations, a marine-type propeller of the variable pitch blade type has been selected as a specific example. Such propeller is shown in perspective view in Fig. 1. However, it is to be understood that the principles 35 of the invention may be used with equal facility in a propeller or pump impeller either of the variable pitch blade type or detachable, non-adjustable blade type or otherwise. Hence, the present illustrations are not to be considered restrictive in any way as to the field of 40 application of the invention since such illustrations primarily serve in an explanatory capacity.

Referring to Fig. 1, the fragmentary outer end of a propeller shaft 10 is shown, this being secured by conventional means such as bolts 12 to the forward end of 45 the hub casing 14. A plurality of blades 16 extend substantially radially from the hub casing 14 and, in the specific embodiment illustrated herein, said blades simultaneously are variable in pitch relative to the hub casing by mechanism to be described hereinafter.

50 In the construction illustrated herein for purposes of describing one preferred embodiment of the invention, the hub casing 14 is hollow for purposes of accommodating means by which the blades are connected to the hub as well as means operable to vary the pitch of the blades.

55 For example, suitable means such as an annular flange 18 is provided for each blade. Viewed in the direction of the axis of the propeller shaft 10, the annular flanges 18 are spaced equally apart circumferentially around the interior of hub 14. Said flanges comprise fixed bearings 60 which preferably have suitable bearing surfaces such as bronze metal 20 affixed to the inner diameter surface as well as on the inner and outer surfaces of the bearing flanges 18 which are parallel to each other.

Each of the annular flanges 18 supports a socket member 65 or element 22 which has a preferably cylindrical socket 24 therein and a fixed annular flange 26 adjacent the outer end of the socket. The flange 26 of each socket element slidably engages the outer bearing coating 20 of the supporting annular flange 18 and a transversely split 70 removable flange 28 surrounds the socket element 22 and slidably engages the inner bearing surface 20 of the annular flange 18. Split ring members 30 are received in a

suitable annular groove 32 in the socket element 22 for purposes of holding the removable flange 28 in operative position. The removable flange 28 is held against relative rotation with socket element 22 by key 34.

A blade adjusting shaft 36 extends axially through the propeller shaft 10 into the hub casing 14 and a cross-head 38 is fixed to the outer end thereof. Each of the removable flanges 28 also serve as a crank ring and have suitable projections supporting a crank pin 40 shown best in dotted lines in Fig. 2. A connecting rod 42 is pivotally connected between each crank pin 40 and the cross-head 38, whereby, as the adjusting shaft 37 is reciprocated longitudinally in either direction relative to the propeller shaft 10, all of the socket elements 22 will be rotated about the axes thereof simultaneously in the same direction. As is clear from Fig. 2, coupling members 44 are fixed to the cross-head 38 and are pivotally connected to the rearward end of each of the connecting rods 42.

Each of the socket elements 22 receive the shank 46 of one of the blades 16. As has been stated hereinabove, one of the principal objects of the invention is to provide means for detachably connecting blades to the hub of a propeller and, more particularly to provide actuating means for the connecting mechanism which may be operated externally of the blade and hub when it is desired to connect a blade to the hub or detach it therefrom.

One embodiment of preferred connecting mechanism is illustrated in the drawings and, essentially, comprises two supplementary connecting means having different but related functions. One of these connecting means is for purposes of resisting relative movement between the propeller blades and the socket members 22 in a direction axially of the blades. The mechanism for accomplishing this comprises an annular, interrupted flange 48 formed on the inner end of each socket element 22, while a complementary annular interrupted flange 50 is formed on the inner end of shank 46 of each blade. The interrupted flanges 48 and 50 of the socket elements and blade shanks function similarly to bayonet-slot connecting means, whereby the blade shank 46 initially is inserted axially into the socket 24 of the socket element 22 and, after the projecting portions of flange 50 have passed between the projecting portions of flange 48, the blade is then rotated about its axis a sufficient distance to place the projecting portions of each of said interrupted flanges in opposition to each other, whereby relative axial movement between the socket element and blades is prevented.

Preferably, the inner end of the socket element 22 is provided with a sealing cover 52 which may be bolted or otherwise securely attached over the opening in the inner end of the socket element. Said cover prevents the leakage of any hydraulic fluid from within the hub casing 14 into the sockets of the socket elements, or the passage of any extraneous external material such as water into the interior of the hub casing.

In the exemplary embodiment of the invention illustrated and described herein, each blade is provided with a flange-like, annular blade palm 54 which preferably is received within a complementary circular cavity 56 formed in the hub casing 14. After the blade 16 has been connected to the socket element 22 by means of the interrupted flanges 48 and 50 as described above, the blade also preferably is keyed to the socket element 22, to prevent relative rotatable movement about the axis of the blade and socket elements, by means of several keying pins 58 for example, which are fitted into suitable axially aligned openings in each socket element 22 and each blade palm 54, as clearly shown in Fig. 4. Threaded locking plugs 60 are also threaded into the blade palm 54 so as to abut the keying pins 58 and, preferably, the plugs 60 are threaded into the palm sufficiently that they tend to move the blade shank 46 slightly outwardly relative to the socket elements so as to place the abutting members of the interrupted flanges 48 and 50 in firm engagement with

each other and thereby prevent any further axial movement of the blades relative to the socket elements 22 in the propeller.

If desired, a soft nose element 62 may be provided on the inner end of each locking plug 60. Due to the bending of the blade shank during operation from the thrust loads placed against the same, there is a tendency to overload the locking plug 60 at least on the forward sides of the blades and the soft nose elements 62 prevent excessive loads on the locking plugs from harming the threads thereon since the elements 62 will absorb any such excess loads.

The second of these supplementary connecting means used to secure each blade shank 46 in the socket elements 22 comprises a pair or set of coengaging clamping rings 64 and 66 which function in a wedging capacity. The inner ring 64 preferably has a cylindrical inner surface which engages a complementary cylindrical surface 68 on the inner end of the shank 46. The outer surface of ring 64 is tapered as is clearly shown in Figs. 2 through 4. Said taper is complementary to and cooperates with a similarly tapered surface on the interior of clamping ring 66, the angle of said taper preferably being greater relative to the axis of the shank than a second tapered surface 25 also formed on ring 66, said latter tapered surface being complementary to conical surface 72 formed on the shank 46 of each blade between the cylindrical portion 68 thereof and the palm 54.

The principal purpose of the clamping rings 64 and 66 is to engage longitudinally spaced portions of the shank of the blade preferably respectively adjacent the outer and inner ends of the socket 24 in the socket element 22. Such arrangement provides an efficient bracing effect between the shank 46 of the blade and the socket element 22. Both of these rings are split at one portion so as to permit limited expansion and contraction thereof in order that the desired clamping function of the rings, which takes place in a wedging manner, may be effected suitably, by means now to be described.

The clamping function of the rings 64 and 66 is achieved by means of a plurality of circumferentially spaced actuating members comprising bolts or threaded rods 74. The inner ends of the bolts or threaded rods 74 are threaded into suitable openings formed in the inner clamping ring 64 as is clearly shown in Figs. 2 and 4, while where the members 74 are bolts, the head ends 76 thereof are disposed near the outer surface of the blade palm 54 as is clearly shown in Fig. 4 particularly, said bolt heads engaging suitable annular shoulders formed in the blade palm 54. These heads 76 may be of any suitable type such as socketed so as to be operable by appropriate wrenches of the Allen type, or otherwise.

The clamping rings 64 and 66 are held preferably against rotation relative to the blade shank 46 by suitable means such as pins 78 and 80 which fit into axially extending slots formed respectively in the clamping rings 64 and 66 as shown in said figure. When final clamping of the blade shank 46 in each socket element 22 is to be made, the bolts or threaded rods 74 are progressively and successively tightened from the exterior of the propeller so as to move the inner clamping ring 64 axially outward, thereby slidably moving the outer clamping ring 66 outwardly relative to the socket 24 until the tapered surface 70 thereon is wedged as firmly as possible against the tapered surface 72 on the shank 46. The split in the ring 66 is sufficiently wide to permit said ring to be contracted suitably to allow as much wedging action as is necessary to take place in the manner described.

It will be seen from Fig. 4 particularly that the outer surface of the outer clamping ring 66 preferably is cylindrical and therefore complementary to the inner walls of the socket 24, said outer surface of ring 66 being relieved intermediately of the opposite ends thereof, if desired, as shown in Fig. 4. Co-engagement between the

walls of socket 24 and the outer surfaces of the outer end portion of ring 66 will move the opposite tapered surface of said ring against the tapered shank surface 72 and effect the desired wedging action between the tapered surfaces 70 and 72 of the ring and blade shank, as best seen in Fig. 4, whereby what may be termed the outer portion of the shank 64 is firmly and wedgingly clamped within the socket element 22.

Simultaneously with the clamping and connecting function just described relative to the tapered surface 70 of clamping ring 66, the other tapered surface thereon which is complementary to the tapered surface on inner clamping rings 64 causes said inner ring 64 to be wedgingly and firmly contracted into clamping engagement with the cylindrical surface 68 of shank 46 which is adjacent the inner end of said shank which is longitudinally spaced from the portion of the shank engaged by ring 66. Hence, when the actuating members 74 for the connecting means, comprising clamping rings 64 and 68, have been threaded into inner clamping ring 64 as far as possible, the shank 46 of each blade is firmly and wedgingly clamped within the socket element 22 at longitudinally spaced portions of said shank and socket element, whereby the blade connecting means is capable of successfully resisting vibrations and other operational stresses imposed upon the blades during use thereof. Further, in the preferred embodiment of the invention, locking plugs 82 are threaded into suitable sockets communicating with the outer ends of those which receive the bolts or threaded rods 74 so as to engage the outer ends of the latter and prevent movement thereof in unthreading direction relative to the inner clamping ring 64.

As an alternative to the use of bolts 74 which have heads 76 on the outer ends thereof engageable with annular shoulders in the blade palm 54, rods which are threaded on the inner ends thereof may be substituted for the bolts 74 and the inner ends of said rods are threaded through the inner clamping ring 64 so as to engage the bottom surface of the socket 24, whereby said rods act as jack screws to force the inner clamping ring 64 away from the bottom of the socket element 22. Under these circumstances, the outer ends of the rods need not have a bolt head thereon but should be provided with some suitable means such as sockets to be engaged by an Allen wrench or the like for purposes of rotating the rods. However, under these circumstances, locking means such as plugs 82 preferably should be used to engage the ends of the threaded rods. No specific illustration of these rods is made due to a close resemblance thereof to the bolts 74.

From the foregoing, it will be seen that the connection of the blades 16 to the socket elements 72 is achieved by connecting means which are operable from the exterior of the blades and hub of the propeller, whereby under normal condition of operations, it is not necessary to enter the hub casing 14 for any purposes regarding the connection or disconnection of the blades relative to the hub. When, for any reason, it is desired to disconnect one of the blades from the hub, it is only necessary to remove the locking plugs 60 and 82 from the hub; rotate the bolts or threaded rods 74 in unclamping direction, which initially results in the bolts being threaded outward relative to ring 64 since the clamping engagements between the rings 64 and 66 and the blade shank and socket still are tight; and then tapping the outer ends of the bolts or rods 74 so as to move the inner clamping ring 64 axially inward.

Said rings are provided with additional means to move the outer clamping ring 66 to inoperative position. Said additional means comprises, for example, an annular shoulder 84 which is engageable with a ring 86 disposed partly in a suitable annular groove in the inner surface of the inner end portion of ring 66 as is best shown in Fig. 4. When the outer ends of the bolts or rods 74 are tapped to move the inner ring 64 inward as described above, engagement of the shoulder 84 with ring 86 results

in the outer clamping ring 64 being withdrawn from wedging engagement between the socket wall 24 and the conical surface 72 on the shank 46 of the blade. This thereby releases the blade and socket element from all influence by the clamping rings 64 and 66. Upon removal of the locking pin 58, the blade then may be rotated axially so as to effect disengagement of the interrupted locking rings 48 and 50 with each other, whereupon the blade may be removed entirely from the socket element 22.

In addition to the sealing effect afforded by cover 52 of the inner end of socket element 22, further sealing members preferably are provided such as a fixed annular sealing shoe 88 which is disposed in a suitable recess in hub casing 14 and slidably wipes against the inner surface of blade palm 54 when the blades are adjusted in pitch. Still further, a compressible annular sealing ring 90 may be disposed between the outer end of the wall defining socket 24 and the shank 46 adjacent the outer extremity of the tapered surface 70 thereon.

From the foregoing, it will be seen that the present invention provides connecting means for detachably clamping the shanks of blades in sockets or socket elements in the hubs of propellers or impellers, said connecting means being operable by means arranged to be actuated from the exterior of the blades and hub of the propeller or impeller. Said connecting means not only withstands bending moments between the blade shanks and the socket elements to which they are connected when the invention is applied to a propeller or impeller of the variable pitch blade type, but any such bending moments also are withstood between the blade shanks and the hub of the propeller or impeller in the event sockets to receive such shanks directly are provided in the hub member. The connecting means also include elements which prevent relative movement between the blades and sockets of the hub in a direction axially of the blades. Further, the connecting means also are arranged preferably to engage the shank of the blade adjacent opposite ends thereof so as to afford as efficient resistance to bending moments as possible. Maximum efficiency of connection also is provided with a minimum of space required in the hub. Further, all elements employed in the structure comprising the invention may be made from any suitable material dictated by the medium within which the propeller or impeller is to be used. Where in the appended claims, the term "propeller" is used, it is to be understood that said term is used in the generic sense applying equally to both propellers and impellers for pumps and the like.

50 While the invention has been shown and described in its several preferred embodiments, and has included certain details, it should be understood that the invention is not to be limited to the precise details herein illustrated and described since the same may be carried out in other ways falling within the scope of the invention as claimed.

We claim:

1. A propeller comprising in combination, a hub having substantially cylindrical radially extending sockets extending substantially radially thereinto, blades each having a shank thereon received respectively within said sockets, said shanks being tapered, a plurality of clamping rings in each socket having complementary interengaging tapered surfaces and engageable with said shanks at longitudinally spaced positions, and means operable to move said clamping rings into firm clamping engagement with said shanks and the interior surfaces of said sockets so as to connect said blades firmly to said hub.
2. A propeller comprising in combination, a hub having sockets extending thereinto at spaced locations in said hub, blades having shanks extending respectively into said sockets, connecting members including a plurality of tapered wedging means interengaging each other within

each socket between the end of the shank of the blade within the socket and the interior of the socket and operable firmly to clamp said shanks within said sockets, and operating means engageable with said tapered wedging means and operable from the exterior of said hub to move said wedging means into firm engagement with said shanks and sockets.

3. A propeller comprising in combination, a hub having sockets therein, blades having shanks extending into said sockets, connecting means on the inner ends of said shanks and interior of said sockets comprising radially extending interengageable interrupted flanges operable to interlock by fractional rotation to prevent relative axial movement between said blades and sockets, and additional connecting means comprising a plurality of annular tapered wedging means surrounding each shank within each socket and respectively clampingly engaging each shank at longitudinally spaced positions thereon within said sockets, whereby said blades are firmly clamped to said hub to resist loosening in said sockets by vibration and operational stresses.

4. A propeller comprising in combination, a hub having substantially cylindrical sockets therein, blades having shanks extending into said sockets, connecting means on said shanks and within said sockets comprising interengageable interrupted flanges adjacent the inner ends of said shanks and operable to prevent relative axial movement between said blades and sockets, additional connecting means comprising a plurality of annular tapered wedging means surrounding each shank within each socket and respectively clampingly engaging each shank at longitudinally spaced portions thereon within said sockets, and means interconnected within said sockets to at least one of said connecting means and operable from the exterior of said hub to move said additional connecting means into firm contact with said shanks of said blades.

5. A propeller comprising in combination, a hub having sockets extending substantially radially thereinto at spaced locations in said hub, blades having tapered shanks extending respectively into said sockets, rings surrounding each shank within each socket, one of said rings having two tapers and one of said tapers being complementary to the taper of said shank, the other ring having a taper complementary to the other taper of said one ring and engageable therewith, and means interengageable with said rings and operable to move the same into firm clamping engagement with longitudinally spaced portions of said shanks.

6. A propeller comprising in combination, a hub having sockets extending substantially radially thereinto at spaced locations in said hub, blades having shanks provided with tapered and cylindrical portions thereon received within said sockets, a set of rings surrounding each shank within the socket therefor, one ring of each set having two tapered portions and one of said tapered portions being complementary to the tapered portion of said shank and engaging the same, the other ring having a tapered portion complementary to the other tapered portion of said one ring and a cylindrical portion engaging the cylindrical portion of said shank, and means engageable with one of said rings and operable to move the same and the other ring into firm clamping engagement with longitudinally spaced portions of said shanks, one of said portions being said cylindrical portion.

7. A propeller comprising in combination, a hub having sockets extending substantially radially thereinto at locations spaced around said hub, blades having tapered shanks extending respectively into said sockets, split rings surrounding each shank within each socket, one of said rings having two tapered portions and one of said portions being complementary to the taper of said shank and engaging the same, the other ring having a tapered portion complementary to the other tapered portion of

said one ring and engageable therewith, and bolt-like means threadably engaging one of said rings and operable to move said rings into firm clamping engagement with longitudinally spaced portions of the shank surrounded thereby.

5 8. A propeller comprising in combination, a hub having sockets extending substantially radially thereinto at locations spaced around said hub, blades having tapered shanks extending respectively into said sockets, rings surrounding each shank within each socket, one of said rings having two tapered portions and one of said tapered portions being complementary to the taper of said shank and engaging the same, the other ring having a tapered portion complementary to the other tapered portion of said one ring and engageable therewith, and bolt-like means threadably engaging said other ring and operable thereby to move said one ring into wedging clamping engagement between said socket and shank and said one ring simultaneously urges said other ring into wedging clamping engagement with said shank at a position thereon longitudinally spaced from the portion of said shank engaged by said one ring.

25 9. A propeller comprising in combination, a hub having sockets extending substantially radially thereinto, blades each having a tapered shank thereon received respectively within said sockets, a set of clamping rings respectively engageable with each of said shanks at longitudinally spaced positions, one ring of each set being engageable with the other ring of said set to move the latter into engagement with said tapered shank to wedgingly clamp the same within the socket therefor, and means operable to move said one clamping ring of each set into engagement with the other ring of each set and also to cause said one clamping ring of each set to be moved 30 into clamping engagement with said shank to clamp said shanks effectively within said sockets.

35 10. A propeller comprising in combination, a hub having spaced sockets extending substantially radially thereinto, blades each having a tapered shank thereon received respectively within said sockets, connecting means comprising tapered wedging means engageable with the tapers on said shanks to clamp said shanks firmly within said sockets, actuating means operable to move said connecting means into firm clamping engagement with said 40 shanks, and means within said socket and movable in an axial direction relative to said sockets and engageable with said connecting means and operable to move the same axially of said sockets to relieve said shanks from 45 clamping engagement by said connecting means when said 50 blades are to be removed from said sockets.

11. A propeller comprising in combination, a hub having sockets extending substantially radially thereinto, blades each having a shank thereon received respectively within said sockets, clamping rings having portions 55 respectively engageable with said shanks at longitudinally spaced positions and also interengageable with the interior of said sockets to clamp said shanks firmly within said sockets, means operable to move said clamping rings into said clamping engagement with said shanks, and means 60 on said rings movable axially into coengagement to free said rings from clamping engagement with said shanks when said blades are to be removed from said sockets.
